Inventor:
PARK S. HOVIS,
By Hiram B. Swartz City,

UNITED STATES PATENT OFFICE.

PARK S. HOVIS, OF WOOSTER, OHIO, ASSIGNOR OF FORTY-FIVE ONE-HUNDREDTHS TO
CHARLES CURRY, OF WOOSTER, OHIO.

TEMPER-SCREW CLAMP.

1,243,065.

Specification of Letters Patent. Patented Oct. 16, 1917.

Application filed March 6, 1917. Serial No. 152,913.

To all whom it may concern:

Be it known that I, PARK S. HOVIS, a citizen of the United States, residing at Wooster, in the county of Wayne and State of Ohio, have invented a new and useful Temper-Screw Clamp, of which the following is a specification.

My invention relates to improvements in temper-screw clamps for well-drilling mechanisms. Its principal object is to provide improved means for clamping wire cables employed in drilling oil, gas, and Artesian wells, and particularly for clamping more securely the cable which actuates the drill tool, and for quickly releasing such cable in case of fire or other emergency, and for shifting position of the clamp thereon intermittently, as required during the drilling process.

It consists of the novel means and combination of elements employed by me to accomplish said objects, as hereinafter fully set forth and as stated in the appended claims.

My invention is illustrated by the accompanying drawings in which similar letters of reference indicate like parts.

Referring thereto, Figure 1 is a plan view of a temper-screw clamp embodying my invention, a portion of its lower end being cut away for better illustration; Fig. 2 is a similar view showing the clamp partially opened to release its grip on the cable; Fig. 3 is a detail view of a portion of the clamp actuating mechanism, detached; and Fig. 4 is a side longitudinal view of one of my cable-gripping slips, detached.

In the drawings, A, B and C are the fulcrum-axis and pair of lever-arms which constitute the clamp body; D indicates a pair of gripping slips, which are set opposite each other between the adjacent jaws of the clamp transversely, said slips each having a pair of longitudinal grooves d d, adapted to register with the corresponding pair of the opposite slip, so as to engage the wire cable H when passed between them through the orifice formed by their junction; said slips are secured to said adjacent jaws, respectively by means of end lugs e e, having perforations, as shown in Fig. 4, and threaded bolts passed therethrough into the clamp body.

I secure said slips nearer to the clamp axis than heretofore, by cutting a notch—shown

in dotted lines—in each jaw, and also in the inner adjacent edge of the clamp hinge, thereby increasing the grip power of the clamp upon the cable H when the lever-arms B and C are drawn toward each other, as hereafter stated.

Said lever-arms B and C are simultaneously actuated in either direction laterally, by the action of the hand-lever E in connection with the rotary member G, and the bars g and h, which pivotally support said member between their outer ends n n, while their inner ends m m are in operative engagement pivotally with the lower end of the lever-arm B, as shown in Fig. 3. Said rotary member G is perforated with a transverse threaded bore fitted to receive and co-act with the threaded lower end F of the hand lever E, said lower end being bent at about right angles with said arm E, and its outer end f adapted to impinge against the adjacent lower end of the lever-arm C, and its length regulated by said thread at any desired distance from said rotary member.

The lever-arm C is provided with a catch c at its lower end, which is adapted to engage the outer end f of said threaded portion F when said rotary member G is actuated in one direction, said bars g and h co-operating therewith in forcing the members B and C toward each other until said outer end f passes the dead point between said bars, as shown in Fig. 1, thereby locking the clamp automatically.

By reversing the movement of the hand-lever E, the parts are quickly unlocked and drawn apart to the position shown in Fig. 2 whereby the cable H is loosened from the clamp by separation of the gripping slips D'; it may be temporarily held in this open position by the engagement of the outer end f' of the threaded member F' with the catch c in co-operation with the bars g' h', while the cable H is shifted; and, when desired, the hand-lever E' may be drawn back far enough to free the lower end of the lever-arm C' from connection with the lever-arm B', thereby permitting the clamp to be entirely removed from the cable. The lugs b b, which project from opposite sides of the clamp head, and sections of rings a a, indicate the means employed for connecting the clamp with the temper-screw of the drilling mechanism and operated in the usual well known way.

By the means aforesaid, it is apparent that by turning the hand lever E as a crank, the grip of the slips D may be regulated to any desired tension either before or after the gripping of the cable as aforesaid.

Thus, by the action of the rotary member G, accomplished by means of the said threaded extension of the hand-lever E, operable therethrough upon and against the free end of the lever arm C, in co-operation with the bars g h, which connect said rotary member with the opposite lever arm B, as aforesaid, I provide a powerful leverage, capable of being manipulated easily and quickly in the direction and to the extent required, to grip the cable H more readily and securely than heretofore, and also to more quickly and easily free the cable from such grip in case of accidental fire, or other emergency or necessity, as frequently occurs in the process of deep well drilling.

Moreover, in connection with my said clamping mechanism, I shorten the distance between the axis A and the gripping-slips D, and lengthen the lever arms B and C, whereby the gripping power of the clamp is greatly increased, and made more efficient for the purpose.

I am aware that rope clamps comprising a pair of jaws having their free ends clamped together by means of a yoke and set screw or a cam lever, have been used heretofore, and such I do not claim broadly; I am also aware that it is not new to use gripping slips between the jaws of such clamps. But the device set forth, whereby the cable is clamped more securely and quickly than heretofore, and is more quickly released in case of emergency, or removed entirely from between the jaws at pleasure, is new and useful.

Having thus fully described my invention, what I claim as new and desire to secure by Letters Patent is—

1. In a temper screw clamp, the combination with a pair of jaws pivoted together, and gripping slips mounted between said jaws near their axis, of a pair of bars pivotally secured at one end to the free end of one of said jaws, a rotary member axially mounted between the other ends of said

bars, a catch on the free end of the other of said pair of jaws, and a hand lever having a threaded portion at about right angles therewith operable through said rotary member transversely, said threaded portion extended beyond said rotary member so as to engage and co-act with said catch and jaw, and be adjustable thereto by the rotation of said hand lever and said rotary member, substantially as set forth.

2. In a device of the character described, the combination with a pair of lever arms having a common fulcrum axis, of a pair of link bars on the free end of one of said lever arms, a catch on the free end of the other of said lever arms, a rotary member mounted between said link bars, and a hand lever having a threaded portion bent at an angle therewith, said threaded portion operative transversely through said rotary member, and adapted to adjustably engage said catch by the rotation of said hand lever and said rotary member, substantially as set forth.

3. In a device of the character described, the combination with a pair of lever arms having as fulcrum a common axis, of a pair of gripping slips mounted transversely between said lever arms, perforated fastener ears at the ends of said slips respectively, means for engaging said ears, a pair of bars pivotally attached to opposite sides of the free end of one of said lever arms, a rotary member mounted between the free ends of said bars, a hand-lever having a threaded end portion bent at about right angles therewith, a transverse threaded bore through said rotary member adapted to receive said threaded end portion, a catch on the adjacent end of the other of said pair of lever arms, and said threaded end portion extended beyond said rotary member sufficiently to engage said adjacent lever arm and said catch, substantially as set forth and for the purpose specified.

In witness whereof I hereunto set my hand this 1st day of February 1917.

PARK S. HOVIS.

In presence of two witnesses:

CHARLES C. JONES,
HIRAM B. SWARTZ.
